UNITED STATES PATENT OFFICE.

WALTER C. PARMLEY, OF UPPER MONTCLAIR, AND CHARLES GILMAN, OF PLAINFIELD, NEW JERSEY.

EXPANSIBLE-JOINT CONSTRUCTION.

Application filed February 13, 1919. Serial No. 276,855.

To all whom it may concern:

Be it known that we, WALTER C. PARMLEY and CHARLES GILMAN, citizens of the United States, and residents, respectively, of Upper Montclair, in the county of Essex and State of New Jersey, and Plainfield, in the county of Union and State of New Jersey, have invented a certain new and useful Improvement in Expansible-Joint 5 Constructions (C), of which the following is a full, clear and exact description.

This invention relates to a form of joint to be used between abutting units or masses of concrete or similar material for the purpose of providing a substantially watertight joint, and additionally, a joint in which there is sufficient flexibility to permit of slight relative movement between the units or masses of concrete.

10 The present invention seeks to overcome certain disadvantages which are present in the use of ordinary joints, one of which is that when concrete pipes, for instance, have been placed in position, dirt and sand are frequently washed into the joints. Additionally, often much of the mortar or grout used in the joint between the pipes is washed out or wasted through the opening between the adjacent ends of the pipe.

15 Generally speaking, the invention may be said to comprise the elements and the combinations thereof set forth in the accompanying claims.

Reference should be had to the accompanying drawings forming a part of this specification, in which Fig. 1 is a sectional elevation showing abutting pipes embodying my invention; Fig. 2 is a sectional elevation of abutting pipes showing a modified form of the invention; Fig. 3 is a sectional elevation of abutting pipes showing a modified form of my invention; Fig. 4 is a sectional elevation of abutting pipes showing a modified form of my invention; Fig. 5

20 is a sectional elevation of abutting pipes showing a modified form of my invention; Fig. 6 is a sectional elevation of abutting pipes showing a modified form of my invention; and Fig. 7 is a sectional elevation showing the manner in which the invention may be applied to usual constructions such as floors, walls, etc.

25 The underlying construction which we embody in various structures to carry out our invention is the combined use of a strip

of impervious material and a thick coating or mass of some suitable plastic, gum-like substance, such, for example, as a bituminous substance, one edge of the sheet of metal co-operating with the gum-like substance to effect a joint and seal.

30 Referring to Fig. 7 of the drawings, the simplest manner in which the invention may be carried out is there illustrated. 1 indicates a concrete mass or unit, and 2 is an adjacent concrete mass or unit. One of these units is prepared by inserting or embedding therein a thin strip of metal such as indicated at 3, while the other of the units is prepared with a recess 4 which contains a mass 5 of some suitable gum-like substance. The units 1 and 2 are placed in proper position with respect to each other, and the metal strip 3 is caused to be embedded in the mass 5. This engagement between the mass 5 and the strip of metal makes an effective seal so that moisture can not pass around the end of the metal strip 3, and consequently the joint is waterproof and seepage proof.

35 After the units 1 and 2 are brought into proper position as shown, the joint between the units may be filled with concrete mortar or grout. It will be apparent that in addition to the waterproof character of the joint which has just been described, the metal strip will have sufficient flexibility to permit of slight relative movement between the units 1 and 2, and furthermore, the mass 5 being somewhat plastic in nature will effect such movement without breaking the joint.

40 Referring to Fig. 1, we have there shown the application of our invention to the joint between adjacent sections of concrete pipe. The sections are indicated at 6 and 7, one being formed with a bell end, and the other with a spigot end, which is the usual construction.

45 One advantage of our invention is that it may be applied to pipes having usual construction at the end thereof, this being illustrated in Fig. 1, wherein a metal strip 8 which is annular is made of proper diameter to fit upon a portion of the spigot end of the pipe section 7. The annular strip 8 extends beyond that portion of the spigot with which it cooperates, and into the space which is usually between the adjacent ends of the concrete pipe. The surface of the pipe section 7 with which the strip 8 co- 100
105
110

operates is preferably prepared by coating the same with gum-like material, such as tar or other bituminous substance, as indicated at 9. This, as it were, cements the strip 8 in proper place, and prevents the seepage of water around the strip 8 at the portion which is in engagement with the pipe section 7.

Within the bell end of the pipe section 6 a mass 10 of gum-like material is placed, this being preferably placed after the pipe is dry, so that it adheres to the wall of the pipe. When the pipe sections 6 and 7 are assembled the free edge of the strip 8 embeds itself in the gum-like material 10, thus forming an effective seal so that water can not seep past the strip 8 at either edge thereof.

The space between the adjacent pipe sections 6 and 7 may be filled with concrete, mortar or grout on either side or upon both sides of the strip 8.

In Fig. 2 a modified form of the invention is illustrated, in which a metal strip of annular form such as indicated at 11 is molded into the spigot end of the pipe 7 with an edge thereof projecting beyond the pipe. A mass 12 of gum-like material is placed against the wall of the bell end of the pipe 6, and in position so that when the pipe sections 6 and 7 are brought together the end of the strip 11 is embedded in the mass 12. As stated with respect to the showing in Fig. 1, the space between the adjacent pipe sections may be filled with concrete, mortar or grout. In Fig. 3 the pipe 7 is made with the strip 13 molded therein in the same fashion as explained with respect to Fig. 2.

40 The pipe section 6 is provided with a recess in the wall thereof, as indicated at 14. In this recess is placed a mass of gum-like material as indicated at 15, and into this mass 15 the edge of the strip 13 extends, and 45 is embedded when the pipe sections are brought into contact. The space between the ends of the pipe sections may be filled with concrete, mortar or grout.

In Fig. 4 we have shown a combination 50 of the constructions which are illustrated in Figs. 1 and 2. The construction shown in the figure mentioned employs an annular strip of metal 16 which cooperates with the spigot end of the pipe 7 and there is an 55 additional annular strip of metal 17 which is embedded at the spigot end of the pipe 7. The strip 16 cooperates with a coating or mass of gum-like material as indicated at 18, while the metal strip 17 cooperates with a 60 coating or mass of gum-like material indicated at 19. The space between the adjacent ends of the concrete pipe may be filled with concrete, mortar or grout.

The construction which has just been described possesses the advantage of forming

a double seal, thus making doubly sure against the seepage of water through the joint between the pipe sections.

It will at once be apparent that while we have shown in the preceding figures the operation of our invention wherein the metal strip is mounted upon or affixed to the spigot end of a pipe section, that the same results may be attained where the metal strip is carried by the bell end of a pipe section. This is illustrated in Fig. 5. Here the bell end of the pipe section 6 has an annular metal strip 19 embedded therein, the edge of the strip extending from the bell end of the pipe. The space between the metal strip and the inner surface of the bell is filled in with a suitable gum-like material as indicated at 20, and the spigot end of the pipe section 7 carries a mass of gum-like material as indicated at 21, with which the free edge of the metal strip 19 cooperates, thus forming an effective seal. The space between the pipe sections 6 and 7 upon either or both sides of the strip 19 may be filled with concrete, mortar or grout.

90 In Fig. 6 the pipe section 7 at the spigot end thereof has a metal strip 22 and between the strip and that portion of the pipe with which it cooperates is a coating of gum-like material such as indicated at 23, this being substantially the same construction as the similar one shown and described in respect to Fig. 1.

95 The pipe section 6 is provided with a recess or groove 24, and in the groove is placed a gum-like mass 25 into which the free edge of the metal strip 22 extends, and is embedded. The space between the pipe sections 6 and 7 may be filled upon either or both sides of the strip 22 with concrete, 100 mortar or cement.

105 It will be seen from the foregoing description that all of the various forms of the invention shown form effective seals across the joint to prevent seepage, and to permit a limited amount of movement between the adjacent pipe sections. In all instances the tar or similar gum-like material may be positioned in the concrete unit with which 110 it is associated before the unit is in place in the trench in which it is to go, so that in the event that water is present when the concrete units are brought together, the gum-like mass is unaffected and the union between the metal strip and the gum-like mass 115 is not prevented. This is in contra-distinction to certain practices at present in vogue where tar or similar material is used as part of the joint, for in such instances when the tar or similar material is placed after the 120 pipe sections or other concrete sections are in place, and in the presence of water, the tar or similar gummy material does not effect a good adhesion with the concrete mass to which it is applied.

Having described our invention we claim:

1. The combination of two pipes of the bell and spigot design, an annular strip of metal mounted upon the spigot end of one of the pipes, a coating of adhesive material between the strip and the spigot end of said pipe, a mass of plastic material associated with the bell end of the other of said pipes, the edge of said strip cutting into and being imbedded in the mass of plastic material when the pipes are in position and mortar or grout in the spaces between the adjacent ends of the two pipes.

2. The combination of two pipe sections of the bell and spigot design, the spigot end of one of said pipes having a substantially annular surface, an annular strip of metal associated on the said annular surface, a coating of adhesive material between the said strip and the annular surface with which the strip cooperates and a mass of plastic material associated with the bell end of the other of the pipes, the edge of the strip cutting into and being imbedded in the mass of plastic material when the pipes

are in position and mortar or grout in the spaces between the adjacent ends of the two pipes.

3. The combination of two pipe sections of the bell and spigot design, an annular strip of metal associated with the spigot end of one of the pipes, a coating of adhesive material between said strip and the outer surface of the spigot end of the pipe, a recess formed in the bell end of the other of the pipes, a mass of plastic material in said recess, the edge of said strip cutting into and being imbedded in the mass of plastic material when the pipes are in position and mortar or grout in the spaces between the adjacent ends of the two pipes.

In testimony whereof, we hereunto affix our signatures in the presence of two witnesses.

WALTER C. PARMLEY.
CHARLES GILMAN.
